United States Patent Office

Des. 197,584
Patented Feb. 25, 1964

197,584

STACKING TRAY

Fred M. Nascher, Los Angeles, and Jacob L. Schwartz,
Covina, Calif., assignors to Hollywood Plastics, Inc.,
a corporation of California

Filed May 20, 1963, Ser. No. 74,972

Term of patent 14 years

(Cl. D58—12.6)

FIG. 1.

FIG. 2.

FIG. 3.

FIG. 4.

FIG. 5.

FIGURE 1 is a perspective view of a stacking tray, showing our new design;

FIGURE 2 is a top plan view thereof;

FIGURE 3 is a side elevational view thereof;

FIGURE 4 is an end elevational view thereof; and

FIGURE 5 is a bottom plan view thereof.

We claim:

The ornamental design for a stacking tray, as shown.
